UNITED STATES PATENT OFFICE.

GEORGE B. CARROLL, OF RED OAK, IOWA.

SPIGOT.

993,959.

Specification of Letters Patent. Patented May 30, 1911.

Application filed August 22, 1910. Serial No. 578,369.

To all whom it may concern:

Be it known that I, GEORGE B. CARROLL, a citizen of the United States, residing at Red Oak, in the county of Montgomery and State of Iowa, have invented certain new and useful Improvements in Spigots; and I do hereby declare the following to be a full, clear, and exact description of the invention, such as will enable others skilled in the art to which it appertains to make and use the same.

My invention relates to improvements in faucets.

The object of the invention is to provide means whereby the faucet may be actuated with one hand when it is desired to draw liquid.

A further object of the invention is to provide a faucet the valve of which will automatically close.

A further object of the invention is to provide a tray or support on the valve operating handle to hold a vessel and by means of which the valve of the faucet may be conveniently opened.

Other objects and advantages will be hereinafter referred to and particularly pointed out in the claims.

In the drawings:—Figure 1 is a perspective view of my improved faucet. Fig. 2 is a vertical central section of the same. Fig. 3 is a perspective view of the modified form of the invention.

The same numerals refer to like parts in all the figures.

1 indicates a pipe having exterior screw threads 2, near one end, and interiorly threaded at 3, at its opposite end. Screwed into engagement with the threads 3, is the 40 faucet proper, indicated at 4, and provided with an upwardly extended hollow boss 5. The interior of the boss 5, is threaded to receive a plug 6, and below the same is an annular flange 7, and between the latter 45 and the plug is a rubber gasket 8. A cone shape valve 9, engages the inner end of the faucet 4, and is normally seated against the latter as shown in Fig. 2. A curved valve stem extends from the cone shape valve and 50 passes through openings 10 and 11 in the gasket 8 and the plug 6, and projects some distance above the latter as indicated at 12.

Pivotedly mounted on a standard 13, extending up from the faucet 4, is a valve operating lever 15, the outer end of which is provided on its under surface with an in-

clined notch, designed to engage the upper end 12 of the valve stem. The rear end of the operating lever is curved downward to lie close to the pipe 1, and at its end it is 60 provided with a weight 16, and an opening 17. A coil spring 12^a is interposed between the outer end of the operating lever and the plug 6 to act with the weight in automatically closing the valve 9. The upper end 65 of the valve stem is linked or otherwise connected to the operating lever, as shown at 12^b, whereby to retain the parts in their relative position.

A standard 19, on the pipe 1 extends up 70 from the latter adjacent the opening 17 in the operating lever, and it is provided with an opening 20, which registers with the opening 17. A pad lock 21 passes through the registering openings 17 and 20 to lock 75 the faucet against unauthorized persons tampering with it.

Suspended from the outer end of the operating lever is a tray 22. The tray may be of any approved pattern, and at its lower 80 end it is provided with a shelf 23, on which a vessel may be supported when drawing liquid.

In the modification I have shown the operating lever applied to a different form of 85 faucet, having a plug valve 25. The operating lever 26, is secured to one end of the plug valve, and at its inner end it is provided with a weight 27, and an opening 28, and at its outer free end it is connected to a 90 tray 29. A standard 30 having an opening, is located near the weighted end of the lever, by means of which a pad lock may be employed.

A faucet constructed in accordance with 95 my invention renders it possible to place the vessel to receive the liquid and operate the valve with one hand, which is of great convenience, and when the vessel is removed the lever and weight will automatically close 100 the valve.

If desirable a finger operating piece 30, may be arranged on the outer end of the operating lever, and in lieu of a weight, a spring may be employed for automatically 105 closing the valve.

Having thus described my invention what I claim is:

1. In a faucet, the combination with a valve, a stem extending from the valve, a 110 standard on the faucet, an operating lever pivoted to the standard and connected to

the valve stem, a weight on one end of the lever, a second standard on the faucet, the said second standard and the lever having registering openings, adapted to receive a lock.

2. In a faucet, the combination with a valve, a stem extending from the valve, a standard on the faucet, an operating lever pivoted to the standard and connected to

10 the valve stem, a weight on one end of the lever, a second standard on the faucet, the said second standard and the lever having registering openings, a tray suspended from the outer 15 end of the operating lever, the tray being located under the open end of the faucet and adapted to support a vessel.

3. In a faucet, the combination of a pipe into which the faucet is secured, a valve 20 seated against the inner end of the faucet in the pipe, a stem extending from the valve, an operating lever, a standard on the faucet to which the operating lever is pivoted, a second standard having an opening registering 25 with an opening in the operating lever adapted to receive a lock, and a vessel supporting tray suspended from the outer free end of the operating lever.

4. In a faucet, the combination of a valve, 30 a stem extending therefrom, an operating lever connected to the stem, a spring interposed between the faucet and the operating lever, a standard to which the operating lever is pivoted, a weight on one end of the 35 operating lever, a tray suspended from the outer end of the operating lever, and said

tray being located under the open end of the faucet.

5. In a faucet, the combination of a valve provided with a stem, the stem being curved 40 upwardly and extending through the faucet, a pivoted operating lever contacting with the stem, a vessel supporting tray supported on the outer end of the lever, and means tending to close the valve. 45

6. In a faucet, the combination of a valve provided with a stem, the stem being curved upwardly and extending through the faucet, an operating lever pivotally connected to the faucet and to the valve stem, a vessel supporting tray carried on the outer end of the lever, and a spring on the valve stem interposed between the faucet and the lever adapted to close the valve. 50

7. In a faucet, the combination of a valve having a stem, a plug secured in the upper side of the faucet and having an aperture, said stem being curved and extending through the aperture in the plug, an operating lever pivotally connected to the faucet 60 and to the valve stem, a vessel supporting tray carried on the outer end of the lever, and a spring on the valve stem interposed between the faucet and the lever adapted to close the valve. 65

In testimony whereof I affix my signature in presence of two witnesses.

GEORGE B. CARROLL.
